C. H. SMITH,
TONE REGULATOR FOR PHONOGRAHS,
APPLICATION FILED JULY 25, 1918.

1,306,196.

Patented June 10, 1919.

Inventor:
Charles H. Smith.
By Cheever & Cox Atty.

UNITED STATES PATENT OFFICE.

CHARLES H. SMITH, OF CHICAGO, ILLINOIS, ASSIGNOR TO SMITH, BARNES & STROHBER COMPANY, OF CHICAGO, ILLINOIS, A CORPORATION OF ILLINOIS.

TONE-REGULATOR FOR PHONOGRAHS.

1,306,196.

Specification of Letters Patent. Patented June 10, 1919.

Application filed July 25, 1918. Serial No. 246,631.

To all whom it may concern:

Be it known that I, CHARLES H. SMITH, a citizen of the United States, residing at Chicago, in the county of Cook and State of Illinois, have invented a certain new and useful Improvement in Tone-Regulators for Phonographs, of which the following is a specification.

My invention relates to tone regulators for phonographs, and the object of the invention is to provide simple, attractive, and efficient means whereby the volume of sound issuing from the machine may be regulated in accordance with the wishes of the user. 10 To obtain these objects I have provided not only an original form of regulator as a whole, but have also provided certain details of construction which contribute to the utility of the apparatus. These will be 15 understood from the following description and claims taken in connection with the accompanying drawings in which—

Figure 1 is a perspective of the upper portion of a phonograph equipped with my 20 invention. The regulator is here shown pulled forward approximately to the limit.

Fig. 2 is a vertical section, taken from front to rear, of the parts shown in Fig. 1.

Fig. 3 is an elevation drawn to an 25 increased scale, showing more particularly the guiding means and the equalizing mechanism by which the two ends of the regulator are compelled always to move equal amounts. The view is partly in section but 30 is chiefly in elevation, looking toward the left in Fig. 4.

Fig. 4 is a sectional elevation of the tone 35 regulator and a portion of the front of the phonograph adjacent thereto, the plane of section being from front to rear.

Fig. 5 is a plan section on the line 5—5, Fig. 3.

Similar numerals refer to similar parts throughout the several views.

40 While the phonograph itself may assume various forms, I have selected to illustrate a common type in which there is a casing 1, having a cover 2, hinged at the back and 45 closing the sound disk 3, and tone arm 4.

The turn table 5 is supported upon a platform 6 in the casing and the tone arm connects with the rear end of a sound duct 7 which conducts the sound to the front 8 of the machine.

In the design illustrated, the regulator is 50 in the form of a drawer which slides horizontally in the opening 10 in the front of the instrument. It has a panel 12 forming the front and is preferably provided with marginal flanges 13 which lend a finished 55 appearance and contact the front of the instrument when the regulator is closed. The result is that when the instrument is not in use and the regulator is closed the appearance will simply be that of a panel forming 60 part of the instrument itself and giving no idea of its function. It is provided with a handle 15 or any other suitable means by which it may be pushed in or drawn out.

Extending backward from the horizontal 70 and vertical edges of the front panel are horizontal walls 18 and vertical ones 19 forming a hollow rectangle. The horizontal walls have openings 20 in them through which the sound from the duct 7 may escape 75 when the regulator is pulled forward. In the design shown the openings are circular, but the size and shape of them may of course be varied as desired. It will thus be seen that the regulator constitutes a hollow valve 80 closed at the front and having sound openings in its side walls and traveling horizontally like a drawer.

I have provided special guiding means by 85 which the regulator may be supported and guided in its backward and forward movement. In the present case these means consist of stationary V-shaped guides 25 entering V-shaped grooves 26 formed in the vertical walls 19 as best shown in Figs. 3 and 5 90 of the drawings.

I have also provided means for equalizing 95 movement at the two ends to prevent the regulator from becoming cramped or bound in its guideways. The equalizing mechanism consists of a shaft 30 journaled in blocks 31, fastened to the inside of the front panel 8. This shaft passes through horizon-

tal slots 33 formed in the walls 19 of the regulator, thus permitting the regulator to move horizontally, despite the fact that the shaft remains stationary. Pinions 35 are 5 rigidly fastened to shaft 30 and coöperate with racks 36 fastened to the inside of the walls 19 and arranged horizontally over the pinions 35. As the two pinions are of the same size and are compelled to rotate in 10 unison, the travel at one end of the regulator will always be equal to the travel at the other end and thus prevent binding.

When the instrument is not in use the regulator will be closed and the phonograph 15 will have the appearance of having a solid front. When the machine is in use and sound is being produced the volume of sound issuing from the instrument may be regulated by pulling the regulator forward 20 a greater or less amount and thus regulating the amount of opening available through the apertures 20. By pulling the regulator out the full distance and entirely uncovering the apertures 20 the instrument will deliver 25 its full tone.

It is evident that the device is exceedingly simple both in construction and operation. Furthermore, it will always remain in any position in which it is set. Its own 30 weight and friction will hold it in any position, and yet very little force is required to move it from one position to another.

Having thus described my invention what I claim as new and desire to secure by Letters Patent, is:

1. In combination, a phonograph having a duct for delivering the sound and a drawer mounted at the end of the duct and slideable lengthwise thereof, said drawer having 40 walls at the top, bottom and sides, one of the walls having an opening for the emission of sound, the available area of the opening depending upon the position of the drawer.

45 2. A phonograph having a duct for delivering the sound, and a tone regulator consisting of a hollow valve with a front extending across the mouth of the duct, and having walls extending back into the duct, 50 said valve being movable longitudinally of the duct and the walls of the valve having openings through which more or less of the sound may issue depending upon the distance to which the front of the valve is 55 drawn forward from the mouth of the duct.

3. A phonograph having a duct for delivering the sound, a tone regulator mounted in the duct, said regulator having a straight line movement and having a front with 60 walls extending back from it into the duct, said walls having openings whereby, when the regulator is pushed inward to the limit the mouth of the duct will be closed but an outlet will be provided when the front is

pulled forward, and means for guiding the 65 regulator in a substantially straight line lengthwise of the duct.

4. A phonograph having a sound duct, a hollow valve having a front extending across the mouth of the duct, and having walls 70 extending backward into the duct, said walls having openings through which more or less sound may issue, depending upon the position of the valve, and means for guiding said valve in a direction perpendicular to 75 the front of it.

5. The combination, with a phonograph having a sound duct, of a hollow valve having a front extending across the mouth of the duct for closing it and having walls 80 extending backward into the duct, said walls having sound openings therein, and means for guiding the valve lengthwise of the duct.

6. The combination, with a phonograph having a sound duct, of a hollow valve having a front extending across the mouth of the duct for closing it and having walls extending backward into the duct, said walls having sound openings therein, means for 85 guiding the valve lengthwise of the duct, and equalizing mechanism for compelling the opposite sides of the valve to move equal amounts, and thereby prevent the valve from 90 binding.

7. A tone regulator for phonographs in the form of a drawer mounted in the front of the phonograph at the mouth of the sound duct, the drawer having a front for closing the mouth of the duct and having 100 apertured side walls extending inwardly from the front of the drawer, guides fastened to the front of the phonograph for guiding it in the direction of the length of the sound duct, a shaft journaled in the front of the phonograph, pinions fastened to said shaft, and racks fastened to the drawer and engaging said pinions for equalizing the movement at the two ends of the 105 drawer.

8. A tone regulator for phonographs in the form of a drawer mounted in the front of the phonograph at the mouth of the sound duct, the drawer having a front for closing the mouth of the duct and having side walls 115 extending inwardly from the front of the drawer, two of the side walls being arranged vertically and two horizontally, the horizontal walls being apertured for the escape of sound, and a horizontal shaft journaled in the front of the phonograph and having pinions fastened to it which coöperate with racks fastened to the inside of the vertical walls of the drawer, the vertical walls of the drawer being horizontally slotted to accommodate the shaft and permit the drawer 120 to move independently of the shaft.

9. In combination, a phonograph having

a sound duct the mouth whereof is at the front of the phonograph, a tone regulator in the form of a drawer mounted in the front of the phonograph at the mouth of the duct, said drawer having side walls extending inwardly and having openings therein for the issue of the sound when the drawer is pulled forward, and means for moving the drawer backward or forward to regulate the volume of said issuing sound through said openings.

In witness whereof, I have hereunto subscribed my name.

CHARLES H. SMITH.
